UNITED STATES PATENT OFFICE.

ALBERT VERNON RIGBY, OF SHARON, PENNSYLVANIA, ASSIGNOR TO THOS. H. ARMSTRONG, OF FARRELL, PENNSYLVANIA.

ROLLING MILL.

Application filed August 2, 1923. Serial No. 655,316.

To all whom it may concern:

Be it known that I, ALBERT VERNON RIGBY, a citizen of the United States, residing at Sharon, in the county of Mercer and 5 State of Pennsylvania, have invented certain new and useful Improvements in Rolling Mills; and I do declare the following to be a full, clear, and exact description of the invention, such as will enable others skilled 10 in the art to which it appertains to make and use the same.

My invention relates to improvements in rolling mills and more particularly to those of the continuous type in which a plurality 15 of rolling units each consisting of upper and lower rolls, are spaced apart longitudinally of the machine. In adjusting machines of this character for different thicknesses of work and to compensate for temperature 20 changes caused by contact of the rolls with the hot metal, it is rather difficult to properly adjust the several units so that their rolls will have the correct draft, and furthermore, this adjusting operation consumes 25 a great deal of time. It is therefore the object of my invention to provide an improved association of parts whereby the rolls of all 30 units of the mill may be simultaneously adjusted, not only saving a great deal of time, but insuring that the relative adjustments of the several units, shall be absolutely correct.

In carrying out the above end, a further 35 aim is to provide a novel arrangement of adjusting screws for forcing the upper rolls downwardly and taking the upward thrust thereof when operating, and to provide fluid pressure means for quickly raising the rolls to any extent permitted by the screws. 40 With the foregoing in view, the invention resides in the novel subject matter hereinafter described and claimed, the description being supplemented by the accompanying drawings.

45 Figure 1 is a top plan view of a rolling mill embodying my improvements.

Figure 2 is a fragmentary side elevation partly broken away and in vertical section.

In the drawings above briefly described, 50 the numeral 1 designates a conventional form of continuous rolling mill, said mill including a plurality of rolling units U. In the type of mill shown, each unit comprises upper and lower rolls 2 and 3, vertically 55 movable bearings 4 for the upper roll 2, a

pair of parallel vertical guides 5 at each side of the machine for guiding the bearings 4 at such side, and a head 6 at each side of the machine connecting the upper ends of said guides 5. 60

Each head 6 is formed with a pair of vertical cylindrical recesses 7 closed at their upper ends by removable plates 8 and provided with stuffing boxes 9 at their lower ends. Within the recesses 7, are pistons 10 65 from which piston rods 11 extend downwardly, the lower ends of these rods being secured at 12 to the lower halves 13 of the bearings 4, while the upper halves 14 of said bearings are not secured to the rods, but merely have openings 15 through which 70 said rods pass. A fluid-pressure pipe 16 extends along the heads 6, one of these pipes being located at each side of the machine, and is provided with branches 17 discharging 75 into the recesses or cylinders 7, below the pistons 10. It thus follows that when fluid pressure is admitted to the pipes 16, it will raise the pistons 10, consequently raising the rolls 2. For lowering the rolls and 80 receiving the upward thrust thereof when in operation, the mechanical means described below, is used.

Vertical screws 18 are threaded through 85 the central portions of the heads 6 and have their lower ends disposed in contact with thrust bearings 19 carried by the upper halves 14 of the bearings 4, the upper ends of said screws being provided with beveled gears 20 which may be splined thereon. 90 These gears at opposite sides of the machine, are connected operatively by transverse shafts 21 and bevel gears 22 on the ends thereof, said bevel gears 22 being in mesh with the gears 20 as shown. Appropriate bearing brackets 23 are provided for the shafts 21 and these brackets may well have bearings 24 for the hubs of the gears 20. 95

A longitudinal shaft 25 extends above the heads 6 at one side of the machine and is rotatable in appropriate bearings 25' rising from said heads, said shaft having bevel gears 26 meshing with the subjacent gears 20. By rotating the shaft 25 through the instrumentality of any desired means, it will be seen that rotary motion will be simultaneously imparted to all of the screws 18 to effect any desired downward adjustments of the rolls 2, it being understood that suitable provision is made for permitting the cylin- 100

105

110

ders 7 to bleed as the pistons 10 travel downwardly. The weight of the feed rolls however, is at all times carried by the pistons 10 and rods 11 and by admitting the proper amount of fluid pressure below the pistons, the rolls may be raised when the screws are rotated to permit such raising.

By providing the construction shown and described or a substantial equivalent thereof, a simple and compact mechanism is provided for adjusting the upper rolls.

As excellent results are obtainable from the general association of parts disclosed, this association is preferably followed, but within the scope of the invention as claimed, numerous minor changes may be made.

I claim:

1. A rolling mill comprising a plurality of transverse vertically movable rolls, bearings for the ends of said rolls, vertical guides in which said bearings are slidably received, said guides having heads each formed with a pair of horizontally spaced vertical bores disposed at opposite sides of the adjacent roll axis, said bores being closed at their upper ends and having stuffing boxes at their lower ends, pairs of vertical piston rods connected with the aforesaid bearings and passing through said stuffing boxes, said rods having pistons within said bores and the latter having fluid pressure inlets under said pistons, vertically disposed hold-down screws for the aforesaid bearings, said screws passing through the heads of said guides between the piston rods, and means for simultaneously driving the hold-down screws at opposite sides of the mill.
2. A rolling mill comprising a roll, bearings supporting the ends of said roll, vertical guides in which said bearings are mounted for vertical sliding, said guides having heads at their upper ends, each formed with a pair of horizontally spaced vertical bores disposed at opposite sides of the roll axis, said bores being closed at their upper ends and having stuffing boxes at their lower ends, pistons in said bores having piston rods passing through said stuffing boxes and connected with said bearings, fluid pressure inlets into said recesses below said pistons, and hold-down screws

passing through said heads between the piston rods, the lower ends of said screws engaging said bearings.

3. A rolling mill comprising a roll, bearings supporting the ends of said roll, and divided horizontally into upper and lower sections, vertical guides in which said bearings are mounted for vertical sliding, a pair of horizontally spaced vertically disposed fluid pressure cylinders at the upper end of each guide and disposed at opposite sides of the adjacent roll axis, pistons in said cylinders having downwardly extending piston rods, means securing the lower ends of said rods to the lower sections of said bearings, the latter having their upper sections free of attachment to said rods, permitting them to be moved upwardly from the lower bearing sections when changing rolls, vertically movable mechanical means engaging said upper sections of said bearings for normally holding these sections lowered toward the lower bearing sections and for depressing the bearings and roll, and means for admitting fluid pressure into the cylinders below the pistons to raise the bearings and roll.

4. A rolling mill comprising a roll, bearings supporting the ends of said roll and divided horizontally into upper and lower sections, said upper and lower sections having vertically aligned openings at opposite sides of the roll axis, a pair of upright piston rods at each end of the roll, said rods passing slidably through the openings of the upper bearing sections and being secured in the openings of the lower bearing sections, fluid pressure cylinders and pistons associated with the upper ends of said rods for raising them, and hold-down means engaging the upper sections of the bearings to normally hold them in operative relation with the lower sections of said bearings and to depress the bearings and roll, said hold-down means being vertically movable and when raised permitting upward sliding of the upper bearing sections away from the roll and the lower bearing sections.

In testimony whereof I have hereunto affixed my signature.

ALBERT VERNON RIGBY.
